Primary Examiner — Jonathan J Han(74) *Attorney, Agent, or Firm* — Marshall A. Lerner; Steven J. Kim; Kleinberg & Lerner, LLP(57) **CLAIM**

The ornamental design for a shoe as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a shoe in accordance with my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines, and the areas enclosed by broken lines, depict features that form no part of the claimed design.

1 Claim, 7 Drawing Sheets
